E. DEATRICK.
STOCK RELEASING DEVICE.
APPLICATION FILED MAR. 27, 1918.
1,290,110.

Patented Jan. 7, 1919.

UNITED STATES PATENT OFFICE.

EDWARD DEATRICK, OF LANCASTER, PENNSYLVANIA.

STOCK-RELEASING DEVICE.

1,290,110.

Specification of Letters Patent.

Patented Jan. 7, 1919.

Application filed March 27, 1918. Serial No. 225,120.

To all whom it may concern:

Be it known that I, EDWARD DEATRICK, a citizen of the United States, residing in the city of Lancaster and State of Pennsylvania, have invented new and useful Improvements 5 in Stock-Releasing Devices, of which the following is a specification, reference being had to the accompanying drawings.

My invention relates to automatic stock 10 releasing devices wherein the releasing element is controlled by an electric magnet and the primary object of my invention is to provide a releasing device of this character with its elements so constructed that the 15 locking mechanism automatically falls open in case of a fire within the building wherein this device is employed for the purpose of securing stock or animals of any kind.

Another object of the invention is to provide 20 a device of this character which can also be readily opened at the will of the operator by merely pressing an electric push button. Other objects will appear in the course of this specification.

I attain the aforesaid objects by the mechanism 25 illustrated in the accompanying drawing, in which Figure I is a plan view of the entire stock releasing mechanism as it appears after the removal of the cap plate 30 1; Fig. II is a sectional side elevation showing part of the inclosing casing broken away, the chain and tube elements being omitted from this view; Fig. III is a sectional end elevation of the device taken on the line 35 3—3 in Fig. I.

Similar numerals refer to similar parts throughout the several views.

Referring more particularly to the drawings, the locking elements of my invention 40 are carried in a casing made up of the cap plate 1, and the base plate 2. These two portions 1 and 2 are hollowed interiorly so as to conceal and protect the working elements of my invention which will be hereinafter 45 described. The base plate 2 is provided with an integrally formed eye 20 adapted to receive the end link 22 of the lock chain 33. This base plate 2 is also formed with a channel way 6 adapted to receive the sliding 50 bolt 5, said bolt being formed at its inner extremity with a suitable lock-lip 23 adapted to coact with an oppositely disposed lip 24 formed on the adjacent side of the finger 3. This finger 3 is journaled at its ends and 55 near its under side in suitable bearings 25 and 26, so as to afford said finger and its lip

24 a suitable rocking motion back and forth, into and out of engagement with the lock-lip 23. A small coil spring 4 normally holds said finger 3 into a position thrown forward, 60 so that the lip 24 is held in engagement with the lock-lip 23 when the sliding bolt 5 is thrust into position. The sliding bolt 5 is provided at its outer extremity with the eye 21 to engage the opposite end link 27 of 65 the lock chain 33. A spring 7 is spread between the pins 15, 16 and 17, and so disposed as to normally hold the lock-lip 23 in snug position against the opposite lip 24, and so as to also give the sliding bolt 5 an outward 70 impetus upon the releasing of the same. Mounted oppositely to the said finger 3 is disposed the electromagnet 8 in suitable spaced relation with the finger 3. The current carrying wires 9 and 10 of this magnet 75 are protected by the flexible tube 11 after they emerge from the casing. This flexible tube 11 is held in snug position at the point where it enters the casing by means of a clamp cap 13—13', which is made in two 80 portions represented by 13 and 13' and adapted to crowd the tube 11 at the point where it enters the casing. This clamp 13—13' is provided with an eye 28 adapted to receive the end link 29 of the anchor 85 chain 32. The elements 13 and 13' are locked together by means of a set screw 14. Clamps 12 hold the tube 11 in alinement with the anchor chain 32.

Any suitable means may be provided for 90 securing the lock chain about the neck of the animal, as for instance, a swivel pin 30 and ring 31, which is an ordinary form of fastening.

One or more push buttons as represented 95 at 34, and one or more soft fuses as represented at 35, are provided as required to co-operate with the mechanism above described, and so that when a push button is pressed upon, an electric current is thrown through 100 the magnet 8, and likewise when one of the soft fuses is burned out, an electric current is thrown through the magnet 8. The push buttons aforesaid may be located at any convenient point in the building wherein the 105 animal may be secured, as for instance, at the side of a door; and the soft fuses are so located in the building that upon a fire being started within the building, said fuses will be most quickly acted upon by the heat 110 generated by said fire.

In operation, one of these stock releasing

devices is provided for each animal secured within the building, and these devices may be ranged along a manger. The anchor chain 32 is secured to the floor or to the 5 manger. The current wires 9 and 10 are extended and placed in circuit with any suitable electrical source, the soft fuses and push buttons being incorporated within the system as required and as above described. The 10 lock chain 33 is thrown around the neck of the animal and fastened. The sliding bolt 5 is then thrust into the locking mechanism whereupon the lock-lip 23 engages with the 15 lip 24 of the finger 3, and the animal is thereby secured. If the keeper desires to release the animal through the operation of this releasing device, all he has to do is to 20 press one of the push buttons adjacent to a door or other point of entrance to the building; or the same result is effected through one of the soft fuses above described being 25 acted upon by heat. Either of these contingencies will suffice to close the electric circuit, and to throw a current through the magnet 8, thereby energizing the same; whereupon the finger 3 is drawn toward the magnet 8, thereby drawing the lip 24 out of 30 engagement with the lock-lip 23, and allowing the sliding bolt 5 to fall out of the casing by which operation the animal is automatically released.

While I have herein described a certain specific manner and method of constructing and assembling the elements of my said invention, it is understood that I may vary 35 from the same in minor details, not departing from the spirit of my invention, so as best to construct the same to meet all practical requirements.

What I claim to be new and patentable is: 40

A stock releasing device, comprising a lock made up of a casing carrying a projecting, sliding bolt, bearing an interior lock-lip, a rocking finger bearing a lip to co-act with the lock-lip in the sliding bolt, a spring 45 to normally hold the said lips in locked relation, and an electromagnet adapted to disengage the said lips when energized; current wires connected to said magnet and located in a normally open electric circuit; a plurality of push buttons and soft fuses located in said circuit, the first adapted to close the circuit at will, the second to close the circuit under the action of heat; an anchor chain 50 attached to the lock casing; and a tie chain 55 having one end attached to the lock casing and the other end attached to the projecting end of the sliding bolt aforesaid.

EDWARD DEATRICK.
